UNITED STATES PATENT OFFICE

SWAN NILS TEVANDER, OF MAYWOOD, ILLINOIS

SCREW-THREADED CAP FOR COVERING GLASS JARS AND OTHER CONTAINERS AND
METHOD OF MAKING SAME

Application filed October 4, 1926. Serial No. 139,446.

My invention relates to what are known as screw caps which are applied to a jar or container by screwing onto the threaded portion of the jar. The object of the invention is 5 to provide means for producing a cap that may be set very tightly onto the container, so as to insure a tight seal and at the same time furnish means whereby the cap may be easily released.

10 Reference will be had to the accompanying drawings of which Fig. 1 is an elevation of my completed cap.

Fig. 2 is a plan view thereof.

Fig. 3 shows an elevation of the cap in the 15 first step of forming the cap.

Fig. 4 shows a plan of the cap shown in Fig. 3.

Fig. 5 is a sectional elevation through the 20 tools showing the first position of the parts in the operation of changing the form of the cap shown in Figs. 3 and 4 into the finished cap shown in Figs. 1 and 2.

Fig. 6 shows a plan view of the parts shown 25 in Fig. 5 at the completion of the operation of changing the form from that of Figs. 3 and 4 to that of Figs. 1 and 2 showing the tools in a closed position but with the central mandrel withdrawn.

Fig. 7 is a sectional view of the parts 30 shown in the position of Fig. 6 but with the mandrel in place.

With the ordinary screw cap used on jars and other containers for preserves and other material, when a tight seal is desired to be 35 made sufficient to preserve the contents of the jar, the screw cap must be set up very tightly and the ordinary screw cap, when thus used, is frequently set up with a wrench in the hands of the housewife. This wrench is 40 usually arranged to grip the cap by friction, alone and requires a person with quite a strong grip of the hand. Then to release such a cap the same sort of a wrench is generally used, but after the jar has been standing a long time—often for a year or more—the cap sticks so tightly that it is difficult to get it free.

In the formation of my cap I draw up the 45 blanks to the form of Figs. 3 and 4 which is larger than would be desired for an ordinary

screw cap. Then by placing these caps in suitable tools here shown as comprising a base block 2 in combination with radially sliding jaws 3 working against the reciprocating mandrel 4, the smooth side walls 5 of the 55 blank shown in Figs. 3 and 4 are pressed into the threaded portions 6 of the finished cap shown in Figs. 1 and 2. By this operation the surplus metal is forced out into ribs 7 which cross over the threaded portions 60 substantially in conformity with the contour or vertical section of the threaded portion 6.

On the release of the jaws 3 from the position shown by Figs. 6 and 7, the mandrel 4 is released axially from the cap by a vertical 65 and revolving movement, change unscrews the cap from the mandrel.

When the wrench is applied to tighten the 70 cap or release it, the wrench will engage these ribs 7 and thus there is provided not merely a frictional contact of the wrench but positive means that will enable the operator to more easily tighten and release the cap.

In certain classes of packing where these 75 caps are screwed on very tightly, the releasing of the cap may be assisted by tapping slightly onto the ribs 7 and since these ribs 7 cross down over the threads 6 a slight tapping on these ribs causes them to be pushed 80 inwardly and thus, as it were, enlarge the diameter of the screw threaded portions and release the threads sufficiently to permit the cap being freely unscrewed. Yet, the cap 85 may be again applied and again screwed tightly down since the amount of release affected by tapping inward the ribs 7 does not enlarge the diameter of the screw thread portion so greatly as to prevent the housewife using the cap as a stopper or cover for the jar or container while the contents of the same are 90 being consumed, a portion at a time.

What I claim is:—

1. The method of forming a screw threaded cap from a flanged blank which consists 95 in inserting a threaded mandrel in the blank, then causing a plurality of correspondingly threaded, radially movable, segmental dies to close about the flange of the blank and press the latter into the threads of the man-

- drel, said segmental dies being dimensioned to leave spaces between them in closed position into which the excess material of the flange is forced outwardly to form outwardly projecting ribs or folds extending across the threads of the flange.
2. In the method of forming a screw threaded cap as defined in claim 1, releasing the finished cap by unscrewing the mandrel therefrom and then radially withdrawing the segmental dies.
3. The method of forming a screw threaded cap with ribs disposed at intervals crossing its threads which consists in providing a flanged blank, inserting a threaded mandrel therein and applying radial pressure externally to the flange over a plurality of spaced segments thereof, thus causing said segments to conform to the flanged mandrel and permitting the intermediate portions of the flange to compose ribs projecting from the external threaded surfaces of the flange and extending transversely of the threads thereon.
4. The method of producing a screw-threaded cap which consists in first forming a flanged blank with a flange of larger diameter than is wanted in the finished cap, then pressing spaced segments of the flange radially inward while permitting the material in the spaces to bend or buckle to form outwardly projecting radial ribs, the inward pressure being exerted against a threaded mandrel, whereby threads are formed in the segmental portions of the flange simultaneously with the formation of said ribs.
5. The method of producing a screw-threaded cap which consists in first forming a flanged blank with a flange of larger diameter than is wanted in the finished cap, then pressing spaced segments of the flange radially inward against a threaded mandrel while permitting the material in the spaces to bend or buckle outwardly without any substantial stretching of said material, thus forming radially projecting ribs at intervals between the thread portions of the flange.
6. A flanged sheet metal cap having a screw thread pressed in spaced segments of its flange and separated by ribs which extend transversely of the direction of the threads, and which consist of gathered portions of the material crimped or bent to project radially outward, said ribs representing the initially excessive sides of the flanged blank, and thus comprising material which has been subjected to substantially no more stretching strain than the remaining material of the flange.
- 60 Signed at Chicago, in the county of Cook and State of Illinois this 27th day of Sept., 1926.

SWAN NILS TEVANDER.
